REFRIGERATING APPARATUS

Edward Heitman, Detroit, Mich., assignor to Kelvinator Corporation, Detroit, Mich., a corporation of Michigan

Application September 23, 1932, Serial No. 634,505

4 Claims. (Cl. 62—126)

This invention relates to refrigerating apparatus, and more particularly to refrigerant evaporators for use in such apparatus.

One of the objects of this invention is to provide an improved refrigerant evaporator of large heat capacity and one which has a large area exposed to the medium surrounding the evaporator for absorbing heat rapidly to maintain low temperatures in the refrigerating compartment in which it is placed.

Another object is to provide an improved compact refrigerant evaporator, but one which is provided with a large refrigerant containing area exposed to the medium surrounding the evaporator so as to be very effective in the absorption of heat from said medium.

Another object is to provide a refrigerant evaporator which is inexpensive to make, simple in construction and which is constructed of parts which are easily manufactured and assembled.

Another object is to provide an improved refrigerant evaporator which is particularly adapted for refrigerating large show cases, and the like, and which occupies a relatively small space in the case but is very effective in the absorption of heat therein.

Further objects and advantages of the present invention will be apparent from the following description, reference being had to the accompanying drawings, wherein a preferred form of the present invention is clearly shown.

In the drawings:

Fig. 1 is a diagrammatic representation of a refrigerating apparatus embodying features of my invention;

Fig. 2 is a view in cross section, taken along the line 2—2 of Fig. 1;

Fig. 3 is a view shown partly in elevation and partly in cross section of a cooling element embodying features of my invention;

Fig. 4 is a view in cross section, taken along the line 4—4 of Fig. 3;

Fig. 5 is a front view in elevation of a modified form of refrigerating apparatus embodying features of my invention;

Fig. 6 is a view shown partly in elevation and partly in cross section of the cooling element shown in the cabinet in Fig. 5;

Fig. 7 is a view in cross section, taken along the line 7—7 of Fig. 6; and

Fig. 8 is a view shown in perspective of the cooling element shown in Fig. 5 removed from the cabinet.

Referring to the drawings, the numeral 20 des-

ignates a refrigerator cabinet of the well known type used for displaying foods. The cabinet 20 is provided with an insulated display compartment 22. Within the compartment 22, I have disposed my improved refrigerant evaporator or cooling element 25, for cooling the circulating air therein. The evaporator extends throughout substantially the entire length of compartment 21. The cooling element 25 is operatively connected to a refrigerant condensing unit 21 by a liquid supply conduit 29 and a vapor return conduit 30.

In refrigerant evaporators, the rapidity with which the refrigerant evaporates, and consequently the amount of heat which can be absorbed from the circulating air, depends upon the area of surface available for the transfer of heat between the air and refrigerant.

In accordance with my invention, I have provided a compact but large heat capacity refrigerant evaporator and one which has a large area exposed to the medium surrounding the evaporator. This is particularly advantageous in the event it is desired to maintain in a frozen condition certain frozen foods stored therein. As will be noted in Fig. 1, the cooling element is relatively long, narrow and flat-like, and extends substantially from one end of the compartment 21 to the other. This cooling element is preferably constructed of sheet metal and includes an upper sheet metal member 35 and a lower sheet metal member 37 separated by a flat sheet of metal 39 disposed therebetween. The upper sheet metal member and the lower sheet metal member are formed so as to cooperate with the flat sheet 39 to provide separate chambers or headers 40 and 42. The upper sheet metal member 35 is provided with an upwardly extending bent portion 44, which extends substantially the length of the cooling element and serves as a manifold for vaporized refrigerant. As will be noted in the drawings, the top member 35 is provided with downwardly extending side walls 45 having outwardly turned flanges 47 which are secured to plate 39, and the bottom member 37 is provided with upwardly extending side walls 48 having outwardly extending flanges 49 which are secured to plate 39.

In order to provide the evaporator 25 with a large heat transfer surface, I have provided a plurality of hollow, flat-like fins 50, preferably constructed of sheet metal. As will be noted, the hollow fins 50 are substantially rectangular in shape and are formed to provide a substantial space for liquid refrigerant between the walls 55

thereof. In using sheet metal material, the fins can be readily formed by drawing dies. The fins are secured to the sheet metal member 37 so as to be in open communication with the chamber 42. As shown, the fins 50 are arranged in spaced parallel relation, depending from the flat bottom of the sheet metal member 37, and extending substantially across the width of the cooling element and substantially throughout the entire length thereof. The sheet metal member 37 is provided with a plurality of transversely extending openings 47 about which the metal is pressed downwardly as at 52. Outturned flanges 54 are formed about the upper or open ends of the fins 50, which flanges are adapted to seat in the depression 48 and be secured to the sheet metal member 37 to provide a fluid-tight joint therebetween. Fins of this type, as well as the parts 35, 37 and 39, may readily be manufactured by punching and stamping operation, which not only facilitate the manufacture thereof but greatly reduce the manufacturing and material cost. By providing fins of this type together with the provision of the refrigerant headers, there is a large liquid refrigerant area exposed to the medium surrounding the evaporator.

In assembling the cooling element, the fins 50 are inserted through the openings in the bottom wall of the header 42. The flange members 54 of fins 50 are then secured to the flanges 52 of sheet metal member 37, preferably by spot welding. After this takes place, the sheet metal member 37 and fins 50 are, as a unit, dipped soldered. This insures fluid-tight joints between the parts of said unit. The next step in the assembly of the cooling element is to weld, or otherwise suitably secure, the sheet metal parts 35, 37 and 39 together at their edges.

In the cooling element 25, I employ two refrigerants, one in the chamber 40, which is hereinafter called the primary refrigerant, and a secondary refrigerant in the chamber or header 42, which is in open communication with the hollow fins 50. Liquid refrigerant is supplied by the condensing unit to the header 40 through an inlet connection 60 connected to supply conduit 29 and vaporized refrigerant is withdrawn from the chamber 40 through an outlet connection 62 which connects the pipe 30 to manifold 45.

By the present arrangement, the secondary refrigerant is condensed by contacting with the sheet metal plate by the cooling action of the primary refrigerant. By using a secondary refrigerant in the chamber 42, the possibility of developing leaks between the sheet metal parts 39 and 50 is lessened, for the reason that pressures are not created therein since the gaseous refrigerant is condensed as soon as it changes from a liquid to a gaseous state. It is to be understood, however, that the plate 39 may be dispensed with and the evaporator operated with but one refrigerant.

Any suitable condensing unit may be used for supplying refrigeration to the cooling element 25. In the chosen illustration, the unit comprises, in general, a compressor 65, a motor 67 for driving the compressor, a condenser 69, and a high side float 70, which controls the flow of liquid refrigerant to the evaporator 25. The compressor withdraws the gaseous refrigerant from the evaporator through the vapor conduit 30, compresses the gaseous refrigerant and delivers it to the condenser wherein it is liquefied and from which it is delivered to the high side float 70. Preferably, the unit is intermittently operated. In order to

control the operation of the motor 67, I have provided an automatic switch 75 which is actuated, for instance, in response to changes in temperature within the compartment 21 by means of a thermostatic bulb 77 which is associated with the switch. If desired, the switch may be made to operate in response to changes in pressures within the conduit 30 in the well known manner.

In Fig. 5 of the drawings, I have shown my invention in connection with a household refrigerator, designated in general by the numeral 80, for cooling a food storage compartment 83. A cooling element or evaporator 85 is shown disposed within the food storage compartment 83. This refrigerant evaporating element is similar in appearance to the evaporator previously described. However, in this instance, the evaporator is operated with but one refrigerant, although it will be understood that primary and secondary refrigerating systems could also be used in this case.

The cooling element 85 is preferably constructed of sheet metal consisting of an upper sheet metal member 88, which is substantially flat for supporting ice trays 89, and a lower sheet metal member 90, which is also substantially flat. The sheet metal parts 88 and 90 are formed to cooperate and provide a chamber or header 92 therebetween for containing refrigerant. An upwardly extending portion 93 is formed across the top of the upper member to provide a manifold for vaporized refrigerant, which extends substantially longitudinally of the evaporator. The upper sheet metal member 88 and the lower sheet metal member 90 are formed with outturned flanges 97 and 98 which are secured together, such as by welding, to provide the chamber 92 fluid-tight.

This cooling element is similarly provided with a large heat transfer surface by providing a plurality of hollow fins 99 secured to the sheet metal member 90. The fins 99, as shown, are in open communication with the chamber 92 and are adapted to contain a quantity of refrigerant and provide a large heat transfer surface between circulating air in compartment 83 and the refrigerant. The fins 99 are arranged in spaced parallel relation and extend substantially across the width of the cooling element and are attached thereto in the same manner as the fins of the previously described cooling element are attached.

The cooling element 85 may be operated by an intermittently operated condensing element, such as described and shown in Fig. 1 of the drawings. Gaseous refrigerant is withdrawn from the evaporator 85 through a vapor conduit 107, and after being compressed and condensed is returned in its liquid state through pipe 109 to the chamber 92 and the hollow fins 99 to again vaporize and absorb heat from the circulating air passing over the large surface formed by the fins.

From the foregoing description, it will be apparent that I have provided a new and improved evaporator for refrigerating apparatus. With an evaporator of this type, a relatively large food storage and display compartment of a cabinet can be refrigerated and maintained at low freezing temperatures to keep food stored therein in a frozen condition. Moreover, this evaporator, as shown and described, while being provided with a relatively large heat transfer surface is nevertheless as a whole, a small unit in comparison to the size compartment it is capable of refrigerating and consequently occupies little of the space thereof. It will also be seen that I

have provided a new and improved evaporator of the type having primary and secondary refrigerating system. In addition, the evaporator may be economically constructed of sheet metal, such 5 as by punching and forming operations, which greatly reduce the cost of manufacture.

Although only a preferred form of the invention has been illustrated, and that form described in detail, it will be apparent to those 10 skilled in the art that various modifications may be made therein without departing from the spirit of the invention or from the scope of the appended claims.

What I claim as my invention is:

15 1. A sheet metal refrigerant evaporator for refrigerating apparatus comprising, in combination, a pair of sheet metal members secured together to provide a refrigerant header, and a number of different sheet metal hollow refrigerant containing fins having outwardly extending flange portions at one end thereof for securing said fins to said header, said fins being open at the flange ends for receiving refrigerant from said header and said flange portions being secured 20 to said header on the inner side of said header.

25 2. A sheet metal refrigerant evaporator for refrigerating apparatus comprising, in combination, sheet metal material formed to provide a refrigerant header, and a number of different sheet metal hollow refrigerant containing fins having outwardly extending flange portions at one end 30 thereof for securing said fins to the header for secondary refrigerant, said fins being open at the flange ends for receiving refrigerant from said header and said flange portions being secured to said header on the inner side thereof.

one end thereof for securing said fins to said header, said fins being open at the flange ends for receiving refrigerant from said header and said flange portions being secured to said header on the inner side of said header.

3. A sheet metal refrigerant evaporator for refrigerating apparatus comprising, in combination, sheet metal material formed to provide a flat elongated refrigerant header, and a number of different sheet metal hollow refrigerant containing fins having outwardly extending flange portions at one end thereof for securing said fins to said header, said fins being open at the flange ends for receiving refrigerant from said header and said flange portions being secured 10 to said header forming a plurality of transverse refrigerant passages below the header on the under side of said header.

4. A sheet metal refrigerant evaporator for refrigerating apparatus comprising, in combination, sheet metal material formed to provide refrigerant headers for primary and secondary refrigerants, and a number of different sheet metal hollow refrigerant containing fins having outwardly extending flange portions at one end 20 thereof for securing said fins to the header for secondary refrigerant, said fins being open at the flange ends for receiving refrigerant from said header and said flange portions being secured 25 to said header on the inner side thereof.
